UNITED STATES PATENT OFFICE.

ROBERT I. HARRIS, OF PUNTA GORDA, FLORIDA.

CHECK PROTECTOR.

Application filed August 11, 1926. Serial No. 128,683.

This invention relates to improvements in check protectors, an object being to incorporate a device for roughening a portion of the paper after writing a check in an ordinary 5 pocket knife, thus making the check protector always available on the assumption that the owner will always see to it that he has his pocket knife with him.

Other objects and advantages will appear 10 in the following specification, reference being had to the accompanying drawing, in which—

Figure 1 is a plan view of the pocket 15 knife having the check protector incorporated therein.

Figure 2 is a longitudinal section taken on the line 2—2 of Figure 1,

Figure 3 is a longitudinal section taken on the line 3—3 of Figure 1,

Figure 4 is a longitudinal section taken on the line 4—4 of Figure 1,

Figure 5 is a cross section taken on the line 5—5 of Figure 3,

Figure 6 is a cross section taken on the line 6—6 of Figure 3.

As briefly intimated in the foregoing statement of the object of the invention, it is believed reasonably certain that the owner or user of a pocket knife will generally see to it that he has this article with him, and on such assumption the pocket knife has been modified in construction to incorporate a device for protecting checks. The unauthorized alterations of checks may be guarded against by various expedients, one of which is to roughen the paper in the immediate region of the denomination or value of the check after the necessary writing has been done. It is with the latter expedient 40 that the invention is concerned.

The entire device is generally indicated 1, those portions having the characteristics of the ordinary pocket knife comprising the blades 2 and 3, and a plurality of brass or 45 other metallic partition plates 4, 5, 6 and 7. The blades 2 and 3 are situated between the pairs of plates 4, 5 and 6, 7 respectively as plainly shown in Figure 1.

Assembled between the foregoing pairs of 50 partition plates are back springs 8 and 9 (Figs. 2 and 3). These serve as spacers between the partition plates. They are secured together by central rivets 10, these rivets passing through the various partition 55 plates, as well as the handle members 11 with which pocket knives are customarily

equipped. The left ends of the back springs are left free, thus serving to hold the blades 2 and 3 both in the closed and open positions. The blades are mounted upon a rivet 60 12 which serves the additional function of a stop which presently appears.

The partition plates are transversely slotted at 13. The handle members 11 are correspondingly slotted at 14, this arrangement resulting in the opening at the end of the device opposite to the blades, into which a check may be inserted for the purpose of receiving an impression from a pair of plates 15 and 16 situated in said opening. 70 The confronting surfaces of these plates are suitably roughened as at 17, the particular design or style of roughening being immaterial.

A lever 18 has connections 19 with one 75 of the impression plates, the plate selected for illustration being the upper one 15 according to the drawing. The connections consist of a pair of links which are pivoted at 20 to one extremity of the lever 18, and at 21 to a lug 22 on the plate 15. The lever 18 is fulcrumed at 23 at a point close to the connections 19, the long end of the lever extending slightly beyond the end of the device as at 24 so that the user can readily 80 take hold of the lever and raise it sufficiently to move the impression plates together. The latter end of the lever rests upon the rivet 12 which thus acts as a stop to limit 85 the closing movement of the lever and the opening movement of the impression plates. 90

Pins 25 serve the double purpose of assisting in securing the bottom plate 16 in position and of guiding the upper plate 15 in its movements in respect to the bottom 95 plate. The bottom plate is additionally secured by a screw or other similar means 26, thereby holding the bottom plate perfectly rigid. The guide pins pass through portions of the back springs 8 and 9 (Figs. 2 and 4) and through brace members 27 and 28 forming parts of the back springs.

These brace members are formed substantially as shown in Figures 2 and 4. They are turned upwardly and toward the adjacent end of the device, as shown, serving as additional spacers between the partition plates 4, 5 and 6, 7. Both the brace members and the back springs are additionally riveted at 29 and 30, the whole arrangement insuring a rigid construction especially in the region of the transverse open- 110

ing. It is noted that the lever 18 is situated between the partition plates 5 and 6. A close fit is desirable in order that the lever may be frictionally held in the closed position. The lever is reduced at 31 at places adjacent to the fulcrum 23 in order to make room for the connecting links 19. A washer or collar 32 (Fig. 3) mounted on the rivet 29 between the central pair of plates 5 and 6 insures the spacing between these plates and guards against any binding of the partition plates against the lever and the connecting links 19.

The operation is readily understood. The owner or user of the device, desiring to protect a check which he has written, will insert the paper in the opening at one end formed by the various slots 13 and 14 and between the impression plates 15 and 16, whereupon he takes hold of the slight extension 24 (Fig. 3) and moves the lever 18 upon its fulcrum 23 to an opening position. This act serves to move the impression plate 15 toward the stationary impression plate 16, the former being connected with the latter by the links 19.

It is noted that the fulcrum 23 is relatively close to the point of connection with the upper impression plate 15 and that the remainder of the lever at the other side of the fulcrum is relatively long. A relatively light pressure against the point 24 will thus produce considerable pressure on the plate 15 against the paper so that the roughened surfaces 17 are readily impressed. The construction of the device is such that the user has all the advantages of an ordinary pocket knife as well as those of the check protector, the function of one preventing no interference to the function of the other.

While the construction and arrangement of the improved check protector is that of a generally preferred form, obviously modifications and changes may be made without departing from the spirit of the invention or the scope of the claims.

I claim:—

1. A pocket knife having blades and back springs to hold them in position; in combination, a pair of impression plates, means carried by the back springs rigidly holding one of the plates and guiding the other plate, and a movable lever having connection with said other plate for moving it in respect to the rigidly held plate.

2. A pocket knife having blades, back springs to hold them in position, partition plates separating the blades and back springs; in combination, a pair of impression plates, means carried by the back spring rigidly holding one of the plates and guiding the other plate which is movable, a lever fulcrumed upon determined partition plates, and means connecting the lever with said

other impression plate causing movement of said plate in respect to the rigid impression plate upon rocking of the lever upon its fulcrum.

3. A pocket knife having blades, back springs holding them in position, partition plates separating the various blades and back springs, a rivet passing through the partition plates and blades serving as a pivotal mounting for the blades; in combination, a pair of impression plates, means carried by the back springs passing through said plates and guiding the other plate which is movable, a fulcrum means mounted between determined partition plates, a lever mounted upon said fulcrum means normally resting at one end upon said knife-blade rivet which limits the closing movement of the lever, and means connecting the opposite end of the lever with said other impression plate causing movement of said plate toward the rigidly held impression plate upon movement of the lever away from said rivet.

4. A check protector comprising a handle structure including slotted partition plates and spacers therebetween, a pair of impression plates situated in the opening formed by the slots in said partition plates, means carried by the spacers rigidly securing one of the impression plates and guiding the other impression plate, a lever fulcrumed upon said partition plate, and connections between one end of the lever and said other impression plate for moving the latter in respect to the rigid impression plate upon movement of the lever.

5. A check protector comprising handle members and partition plates which are transversely slotted to produce an opening, spacers separating the handle members and partition plates, a pair of impression plates situated in said opening, pins carried by said spacers passing through the impression plates assisting in securing one of said plates against the spacers and guiding the other impression plate, means including a screw carried by the spacers and entering said one of the impression plates to hold the same rigid, a lever fulcrumed between determined partition plates, and means connecting one end of the lever with said other impression plate causing movement of said plate when the lever is moved upon the fulcrum, said connecting means including a pair of links, a lug on said other impression plate, and means pivotally attaching the links to said lever and to said lug respectively.

6. A check protector comprising handle members and partition plates which are transversely slotted to produce an opening in one end, spacers separating the handle members and partition plates including portions extending above the slots serving as braces for the adjacent end of the protector,

- a pair of impression plates situated in said opening, means securing one of the impression plates against the spacers beneath said brace portions, pins passing through the
5 spacers, impression plates and brace portions additionally securing said one impression plate and guiding the second impression plate for movement in said opening, a lever fulcrumed between the partition plates and
10 having a reduced portion adjacent to said second impression plate, a lug on said second impression plate, and means including links attached to the lug and to said lever at said reduced portion for moving said sec-
ond impression plate upon movement of the 15 lever upon its fulcrum.
7. An article of manufacture comprising a handle structure which includes partition plates and back springs serving as spacers, knife blades pivoted between certain partition plates being held in open and closed 20 positions by said back springs at one extremity thereof, a pair of impression plates located in an opening formed by slots in said partition plates, and a lever pivoted between 25 other partition plates having connection with one of the impression plates.

ROBERT I. HARRIS.
